US00D878080S

(12) **United States Design Patent** (10) **Patent No.:** **US D878,080 S**
(45) **Date of Patent:** **** Mar. 17, 2020**

(54) **TOWEL DISPENSER**

(71) Applicant: **San Jamar, Inc.**, Elkhorn, WI (US)

(72) Inventors: **Michael Young**, Mukwonago, WI (US);
Tou Yia Thao, Oakdale, MN (US);
Fusu Thao, Cottage Grove, MN (US)

(73) Assignee: **San Jamar, Inc.**, Elkhorn, WI (US)

(**) Term: **15 Years**

(21) Appl. No.: **29/698,342**

(22) Filed: **Jul. 16, 2019**

Related U.S. Application Data

(62) Division of application No. 29/636,076, filed on Feb. 6, 2018.

(51) **LOC (12) Cl.** **23-02**

(52) **U.S. Cl.**

USPC **D6/523**

(58) **Field of Classification Search**

(57) **CLAIM**

The ornamental design for a towel dispenser, as shown and described.

DESCRIPTION

FIG. 1 is an isometric view of a towel dispenser, showing our new design;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dot-dash broken lines shown in the drawings are boundary lines and the uniform broken lines illustrate portions of the design that form no part of the claimed design.

1 Claim, 7 Drawing Sheets
